SOAP DISPENSING HANDLE FOR FOUNTAIN BRUSH

Leonard Dale Ashley and Charles C. Cooner, Overland Park, and Arthur B. Riordan, Prairie Village, Kans., assignors to Vita Craft Corporation, Kansas City, Mo., a corporation of Missouri

Filed June 8, 1964, Ser. No. 80,330

Term of patent 14 years

(Cl. D9—2)

FIG. 1 is a top plan view of a soap dispensing handle for fountain brush, showing our new design;

FIG. 2 is a side elevational view thereof;

FIG. 3 is an end elevational view thereof; and

FIG. 4 is an elevational view of the other end thereof.

We claim:

The ornamental design for a soap dispensing handle for fountain brush, as shown.
